**PILASTER STRUCTURES AND HINGE
BRACKET ASSEMBLIES**

Kent W. Benham, Gates Mills, Ohio, assignor to The Sanymetal Products Company, Inc., Cleveland, Ohio, a corporation of Ohio
Original application Feb. 26, 1959, Ser. No. 795,683.
Divided and this application Mar. 13, 1961, Ser. No. 136,683.

10 Claims. (Cl. 20—16)

This invention relates to improved pilaster structures and hinge bracket assemblies in which the door supporting hinge brackets are rigidly secured to the jamb edge of the pilaster in cantilever suspension and without attachment to the side faces of the pilaster. This application is a continuation-in-part of my copending application Serial No. 696,864 filed November 15, 1957, now U.S. Patent 2,876,874, issued March 10, 1959, and a division of my copending application Serial No. 795,683 filed February 26, 1959.

Hinge brackets made in accordance with this invention are particularly designed for cantilever attachment to frame structures, posts and pilasters whose jamb edge is of relatively narrow width, and are particularly designed for attachment to the jamb edge of hollow metal pilasters which measure only one to two inches or less in thickness, and which form the supporting uprights for interior cubicles, such as toilet and hospital cubicles, and the like.

A typical hollow metal pilaster with which the hinge brackets of this invention may be associated, may be formed by a pair of spaced metal facing sheets bonded to a reinforcing core of sound deadening insulation, and which present paired inturned flanges along the exposed vertical and horizontal edges thereof. The paired inturned flanges present a pair of outturned lip portions formed integral therewith and joined together by exteriorly applied spot welds to provide a rigid pilaster construction. Edging strips of semi-tubular cross section, and presenting a contoured facing portion and paired inturned lip portions, are telescoped over the outturned lip portions of the pilaster body to interlock therewith. The applied edging strips thus supply a finished appearance to the exposed vertical and horizontal edges of the pilaster.

The improved hinge brackets of this invention may be die cast or otherwise formed as integral units to present a laterally extending door supporting arm section on which the door is swingably mounted. These hinge brackets are designed to be mounted on the jamb edge of a relatively thin pilaster by means which engage or interlock with a jamb portion of the pilaster or with associated parts applied to or built into the pilaster during its manufacture. Where the hinge bracket includes an exterior body section from which the arm supporting section laterally extends, the body section thereof is equipped with means to rigidly secure the same to a jamb edge seating face of the pilaster and between the terminal ends of the contoured jamb facing portions thereof, and with the exposed outer face of the bracket body section in contour symmetry with the outer faces of the contoured jamb facing portions of the pilaster.

The terminal ends of the bracket body section may be equipped with a pair of spaced tongues, wings or studs designed to telescope into the adjacent terminal ends of slidably jamb facing strips to thereby secure, or additionally secure, the hinge bracket in rigid cantilever suspension from the jamb face of the pilaster body.

As modified securing means, a locking channel may be secured to the flat jamb portion of the pilaster body be-

2

tween the terminal ends of the contoured jamb facing portions thereof, and which is designed to interlock with a corresponding female formation on the rear face of the bracket body section.

All forms of this invention feature hinge brackets which are in architectural symmetry and harmony with the adjacent contoured jamb facing sections of the pilaster body, and with the exposed portions of the hinge bracket confined to the jamb edge of the mounting pilaster. The 10 laterally extending door supporting arm sections of these hinge brackets present a pintle hole formed to receive a hinge pintle associated with a bracket counterpart applied to either the upper portion or lower portion of the mounted door. By the use of these hinge brackets, the 15 pilaster is not defaced by bracket side flanges which telescope over the sides of the pilaster and secured thereto by bolts or screws as heretofore used, but on the contrary, the exposed surfaces of these hinge brackets are contoured in blended symmetry with the jamb edge of the 20 pilaster to provide a door supporting structure of architectural harmony and beauty.

These improved pilaster structures and hinge bracket assemblies are so constructed as to insure precise alignment of the upper and lower hinge brackets and accurate 25 hanging of the door without field adjustment. These hinge brackets may be economically die cast or otherwise assembled as an integral unit at substantially less cost than door supporting hinge brackets heretofore made, can be attached to a floor supported or ceiling 30 hung pilaster during manufacture thereof, and as mounted thereon, present an assembly which is substantially free of projections and crevices in which dirt would collect.

Other objects and advantages of this invention will 35 become apparent as the disclosure proceeds.

Although the characteristic features of this invention are particularly pointed out in the claims, the invention itself, and the manner in which it is made and used, may be better understood by referring to the following description taken in connection with the accompanying drawings forming a part of this disclosure, and in which:

FIG. 1 is a fragmentary perspective view of a floor supported pilaster having an upper and a lower hinge bracket made in accordance with this invention mounted on the jamb edge thereof;

FIG. 2 is a fragmentary perspective view of a ceiling supported pilaster having upper and lower hinge brackets made in accordance with this invention and mounted on the jamb edge thereof;

FIG. 3 is a front perspective view of the upper hinge bracket as the same would appear before it is mounted on the upper part of either the floor supported pilaster shown in FIG. 1 or the ceiling hung pilaster shown in FIG. 2;

FIG. 4 is a perspective view of the lower hinge bracket as the same would appear before it is mounted on the lower portion of the floor supported pilaster shown in FIG. 1;

FIG. 5 is a perspective view of the lower hinge bracket as the same would appear before it is mounted on the lower end of the ceiling hung pilaster shown in FIG. 2;

FIG. 6 is a perspective view of the underface of the lower hinge bracket shown in FIG. 5, this view also showing a fragmentary part of the lower end of the ceiling hung pilaster to which the hinge bracket is attached;

FIG. 7 is a fragmentary perspective view of the floor supporting pilaster shown in FIG. 1 and as the same would appear prior to the application of the upper and lower hinge brackets and adjacent edging strips thereto;

FIG. 8 is a fragmentary perspective view of the floor supporting pilaster shown in FIG. 1 as the same would

appear when the adjacent edging strips have been applied to the jamb edge thereof, but without the application thereto of the upper and lower hinge brackets shown in FIGS. 3 and 4;

FIG. 9 is a rear perspective view of the upper hinge bracket shown in FIG. 3;

FIG. 10 is a rear perspective view of the lower hinge bracket shown in FIG. 4;

FIG. 11 is a fragmentary perspective view of the pilaster shown in FIG. 1, this view revealing the anchor block of the upper hinge bracket shown in FIG. 9 or the lower hinge bracket shown in FIG. 10 as applied to the pilaster, certain parts of the pilaster being broken away to illustrate structural details;

FIG. 12 is a rear perspective view of the lower hinge bracket shown in FIGS. 5 and 6;

FIG. 13 is a fragmentary perspective view showing a portion of the lower end of the ceiling hung pilaster prior to the application of the lower hinge bracket thereto, certain parts of the pilaster being broken away to illustrate structural details; and

FIG. 14 is a fragmentary perspective view showing a portion of the lower end of the ceiling hung pilaster after the lower hinge bracket has been applied, certain parts of the pilaster being broken away to illustrate structural details.

FIG. 15 is a perspective view of a further modified form of door supporting hinge bracket and a fragmentary part of its supporting pilaster, this pilaster being generally constructed as indicated in FIGS. 1, 2, 7 and 8, but whose jamb edge has been modified to accommodate this hinge bracket, this view showing only a fragmentary part of one of the edging strips to reveal further details;

FIG. 16 is a fragmentary perspective view of the pilaster body which supports the hinge bracket shown in FIG. 15, and as the same would appear when the interior bracing plate and the exterior bracket supporting snap fastener have been applied to the pilaster during manufacture thereof, but before application of the hinge bracket and adjacent edging strips;

FIG. 17 is a side elevational view of the bracket shown in FIG. 15 and a fragmentary part of the pilaster to which it is applied, certain parts of the interior structure being shown in phantom lines;

FIG. 18 is a front elevational view of the hinge bracket shown in FIGS. 15 and 17, and a portion of the pilaster to which it is applied, certain interior parts thereof being shown in phantom lines; and

FIG. 19 is a horizontal section of the hinge bracket and a portion of the pilaster to which it is attached as the same would appear when viewed along line 19-19 of FIGS. 17 and 18.

Similar reference characters refer to similar parts throughout the several views of the drawings and the specification.

All of the door supporting hinge brackets constructed in accordance with this invention are particularly designed for attachment to the jamb edge of hollow metal posts or pilasters which may be either floor supported as shown in FIG. 1 or ceiling supported as shown in FIG. 2. These door supporting pilasters are particularly adapted for assembly into interior cubicles, such as hospital and toilet cubicles.

The floor supported pilaster 1 as shown in FIG. 1 and the ceiling hung pilaster 1' as shown in FIG. 2, and with which the door supporting hinge brackets of this invention are particularly adapted for attachment, comprise a pair of pilaster facing sheets 2-2 formed from sheet metal or other strong sheet material, which together present inturned flanges 3-3 along the exposed vertical and horizontal edges thereof. Each pair of inturned flanges 3-3 incorporate outturned lip portions 4 which are secured together by suitable spot welds 4' exteriorly applied to the paired outturned lip portions at the crotch area between them as shown in FIG. 7. Prior to spot

welding together the paired inturned lip portions 4 to provide a rigid pilaster construction, a reinforcing and insulating core 5 is first adhesively bonded to the inside face of one of the pilaster facing sheets 2, and the exposed face of the reinforcing core is then coated with adhesive and the other facing sheet 2 then applied thereto. Pressure is then applied to the sandwich as thus formed to insure a firm adhesive bond between the reinforcing core 5 and the inside faces of the pilaster facing sheets 2-2. The reinforcing core 5 is desirably composed of a relatively hard, pilaster sheet bracing and sound deadening insulation packing, such as slabs of fibreglass, honeycomb fibreboard or other core material which is relatively light in weight, capable of deadening sound, and capable of bracing and supporting the pilaster facing sheets 2-2 to which the reinforcing core 5 is adhesively bonded.

The exposed vertical and horizontal edges of the pilasters 1-1' are trimmed by means of edging strips 6 of semi-circular cross-section and similar in size and contour. Each edging strip 6 presents a face portion 6' of generally curvilinear form which terminates in inturned lip portions 7. The edging strips 6 are designed to be telescoped longitudinally over the outturned lip portions 4 of the pilaster facing sheets 2-2, so that the inturned lip portions 7 of the edging strip will interlock with and be firmly secured to the outturned lip portions 4 of the pilaster facing sheets 2-2 as shown in FIGS. 1, 2, 7 and 8.

During manufacture of the sheet metal panel facing sheets 2-2 of the pilasters 1 and 1', suitable cut-outs, deformations or additions may be made in or to those areas of the inturned flanges 3 and outturned lip portions 4 to which the door supporting hinge brackets of this invention are to be applied, to thereby provide suitable seating faces and anchoring means for rigidly securing the selected hinge bracket to the jamb edge thereof, as more fully hereafter explained. All of the hinge brackets of this invention are particularly designed to be applied to the prepared areas of the inturned flanges 3 of the panel facing sheets 2-2, either before the lip portions 4 of the panel facing sheets have been spot welded together, or after the reinforcing core 5 has been positioned between the panel facing sheets and the outturned lip portions 4 thereof welded together as heretofore explained.

The floor supported end of the pilaster 1 as shown in FIG. 1, and the ceiling supported end of the pilaster shown in FIG. 2, are suitably secured to the floor or ceiling wall by suitable brackets and lag bolts 100 as shown in FIG. 2. The floor or ceiling supported end of the pilaster and associated wall securing means, are concealed within a trimming shoe 8 as shown in FIGS. 1 and 2 which snugly telescopes over the pilaster and snugly seats against the horizontal building wall to which the end of the supported pilaster is attached.

The upper door supporting hinge bracket A as shown in FIGS. 3 and 9 is designed for attachment to the upper part of the door supporting pilaster 1 as shown in FIG. 1 or the upper part of the ceiling hung pilaster 1' shown in FIG. 2. The lower door supporting hinge bracket A' as shown in FIGS. 4 and 10 is designed for attachment to the lower part of the floor supported pilaster 1 shown in FIG. 1. Both of the door supporting hinge brackets A and A' are generally similar in form and may be die cast as integral units. Each of the hinge brackets A and A' presents a laterally extending arm section 20 integral with a vertically extending body section 21. The arm section 20 of the upper hinge bracket A has a pintle hole 20' therein designed to receive a pivot pintle associated with a bracket fixture (not shown) which is attached to the upper part of the door to be mounted thereon. The laterally extending arm section 20 of the lower hinge bracket A' has a pintle receiving hole 20'' therein designed to receive and support a hinge pintle on which the bracket fixture (not shown) fixed to the lower part of the door is swingably mounted.

The body section 21 of the upper hinge bracket A as shown in FIGS. 3 and 9 and the lower hinge bracket A' as shown in FIGS. 4 and 10, present a curvilinear outer face 21' which is contoured in conformity with the curvilinear outer face 6' of the adjacent edge moulding strips 6 which are applied to the pilaster body. The body section 21 presents square ends 22, and an anchor block 24 which projects from the rear thereof as shown in FIGS. 9 and 10. The anchor block 24 has a nose portion 25 which projects beyond the upper square end 22 of the body section as shown in FIGS. 3 and 4. The nose portion 25 has an inset abutment face 25' designed to abut against the inside face of the adjacent inturned flanges 3 of the pilaster body as shown in FIG. 11.

The body section 21 of each hinge bracket A and A' also presents relatively flat rear seating face portions 22' extending along the sides of the anchor block 24 and designed to snugly seat against the outer faces of side ledge portions 10' which define the sides of an anchor block receiving hole 10 cut in the inturned flanges 3 of the pilaster body. Each square end 22 of the body section 21 presents a pair of spaced insert studs 23 and 23' which extend vertically therefrom. Each insert stud 23 and 23' is tapered toward its free end, and the base thereof is generally triangular in cross section to thereby telescope into the adjacent interior corner of the edge moulding strip 6 as defined between the inside face of the curvilinear facing portion 6' and the inside face of the inturned lip portion 7 of the moulding strip 6 and the adjacent lip portion 4 of the pilaster.

In manufacturing the pilaster facing sheets 2-2 to form the pilaster 1-1' to which hinge brackets A and/or A' are to be applied, an appropriate cut-out is formed in the inturned flanges 3 thereof so that when the lip portions 4 of the pilaster facing sheets are welded together, an anchor block receiving hole 10 is formed therein as shown in FIG. 7, leaving side ledge portions 10' along the sides of the anchor block receiving hole 10. The outside faces of the side ledge portions 10' provide seats for the rear seating face portions 22' of the body section 21 of the hinge brackets A and A'. It will be noted that the outturned lip portions 44 of the pilaster facing sheets 2-2 are also cut away in forming the anchor block receiving hole 10, and that the terminal ends 4" of the lip portions 4 terminate directly adjacent the upper and lower edges of the receiving hole 10.

The hinge brackets A and A' are applied to the supporting pilaster structure formed as shown in FIG. 7, by tilting the anchoring block 24 thereof into the formed hole 10 so that the abutment face 25' of the nose portion 25 thereof will seat against the inside faces of the inturned flanges 3 directly above the formed hole 10. In the same tilting operation, the end portions of the relatively short upper studs 23 adjacent the abutment face 25' of the hinge brackets A and A', are also tilted under the adjacent terminal ends 4" of the flared lip portions 4 of the pilaster body and into bearing abutment against the inside faces the lip portions 4 thereabove. Upon completion of the tilting operation, the side edges of the ledge portions 10' which define the hole 10 will then be substantially in abutment with the adjacent sides of the anchor block 24, and with the rear face portions 22' of the bracket body section 21 seating against the outside face of the pilaster edge portions 10'. It will be noted by referring to FIGS. 3, 4, 9 and 10 that the paired studs 23' extending from the lower end of the body section 21 of the hinge brackets A and A' are longer and spaced slightly further apart than the paired studs 23 extending from the upper end of the body section 21. This permits the end portions of the paired insert studs 23' at the lower end of the body section 21 to be telescoped over the terminal ends 4" of the adjacent outturned lip portions 4 of the pilaster body and extend under the inner faces of the adjacent lip portions 4 extending downwardly therefrom. Upper and lower edge moulding strips 6 are

then telescoped over the outturned lip portions 4 of the pilaster body until the terminal ends thereof abut the adjacent square ends 22 of the body section of the mounted hinge bracket, to thereby provide substantially flush and single line joints therebetween. It will be noted that the abutment face 25' of the nose portion 25 and the underface of the adjacent insert studs 23 are spaced apart for a distance slightly more than two thicknesses of sheet metal, to thereby permit the adjacent terminal ends of the inturned flanges 3 of the pilaster body, and the adjacent terminal ends of the lip portions 7 of the edging strip, to telescope therebetween. The paired upper studs 23, which are of shorter length than the abutment face 25' of the nose portion 25 as shown in FIGS. 3 and 4, are also in bracing abutment against the inner face of the adjacent pilaster lip portions 4 which prevents lateral movement of the body section 21 of the hinge bracket A or A'.

The hinge brackets A and A' are securely and rigidly anchored to the jamb edge of the pilaster 1 or 1' by the nose portion 25 whose inset abutment face 25' snugly abuts the inside face of the adjacent terminal portions of the inturned flanges 3 of the pilaster body, and with the lower end of the anchor block 24 seating on and supported by the adjacent horizontal edge of the pilaster flange portions 3-3 which defines the lower edge of the anchor block receiving hole 10, as shown in FIG. 11. The hinge brackets A-A' are also braced by the rear seating face portions 22' of the bracket body section 21 which snugly seat against the outside faces of the ledge portions 10' of the inturned flanges 3 which are adjacent the anchor block receiving hole 10. The hinge brackets A and A' are additionally rigidly anchored by the paired insert studs 23 and 23' extending from both ends of the bracket body section 21 and project into the end of the adjacent semi-tubular edging strip 6 and thus locked in bracing relation against the inside face of the curvilinear facing portion 6' of the edging strip 6 extending thereover, and the inside face of the adjacent underlying inturned lip portions 7 of the edging strip 6, and the adjacent face of the outwardly flared lip portion 4 of the pilaster.

The door supporting hinge brackets A and A' can be inexpensively made as integral castings, and when mounted on the jamb edge of the pilaster body as shown in FIGS. 1 and 2, are in streamline symmetry with the edging strips 6, and provide an assembled door supporting pilaster structure which is strong and rigid, long lasting in use, and is highly attractive and pleasing in architectural appearance.

The door supporting hinge bracket B as shown in FIGS. 5 and 12, is designed for attachment to the lower corner of a ceiling hung pilaster 1' as shown in FIG. 2. The hinge bracket B presents a door supporting arm section 20 extending laterally from its body section 21, the arm section 20 having a hinge pintle receiving hole 26" therein to which the lower end of hinge pintle may be fixed and on which a suitable bracket fixture (not shown) attached to the lower end of the door may be swingably supported. The body section 21 of the hinge bracket B presents a curvilinear outer face 21' and a square cut upper end 22. The body section 21 also has an anchoring block 24 projecting rearwardly therefrom and which presents a nose portion 25 extending from the upper end thereof which has an inset abutment face 25'.

The square cut upper end 22 of the hinge bracket B presents a pair of spaced insert studs 23 projecting vertically therefrom. Its body section 21 also presents a pair of rear seating faces 22' extending along the sides of the anchor block 24, and which are designed to snugly seat against the outside faces of adjacent ledge portions 11', which extend along the vertical sides of an anchor block receiving hole 11, formed by cutting away inner

parts of the vertically extending inturned flanges 3 at the lower end of the pilaster body, as shown in FIG. 13.

The hinge bracket B also features a wing section 26 as shown in FIGS. 5, 6 and 12 which extends rearwardly from the lower end of the anchor block 24. The wing section 26 has a curvilinear outer facing portion 6' in shaped conformity to the curvilinear outer facing portion 6 of the edging strip 6 which extends along the lower horizontal edge of the ceiling hung pilaster 1' as shown in FIG. 6. The wing section 26 presents a square cut end 27 designed to snugly abut against the terminal end of the adjacent horizontal edging strip 6. The wing section 26 also presents a pair of spaced inner rail portions 28 designed to seat against the adjacent horizontal ledge portions 11" extending along the horizontal sides of the anchor block receiving hole 11, formed by cutting away inner parts of the horizontally extending inturned flanges 3 of the pilaster body as shown in FIG. 13. The inside face of the wing section 26 also presents a depressed center face 28' between the rail portions 28, in which the lower leg of a Tinnerman nut 12 may be pocketed as shown in FIG. 13. The lower hinge bracket B may be die cast from a suitable metal in integral form.

The lower corner of the ceiling hung pilaster 1 which is to receive the hinge bracket B, is formed as shown in FIG. 13 by cutting an angular shaped hole 11 in the lower ends of the vertical inturned flanges 3 and the adjacent ends of the horizontal inturned flanges 3 of the pilaster body, thereby leaving vertical side ledge portions 11' and horizontal side ledge portions 11". The vertically extending outturned lip portions 4 of the pilaster body terminate directly adjacent the upper transverse edge of the hole 11, and the horizontally extending outturned lip portions 4 terminate slightly short of the lower transverse edge of the hole 11, to thereby permit the telescopic application of a Tinnerman nut 12 over the hole defining transverse edges of the horizontal inturned flanges 3 as shown in FIG. 13.

The corner bracket B is applied to the pilaster body by tilting the anchoring block 24 thereof into the hole 11 of the pilaster body, with the abutment face 25' of its nose portion 25 in seating engagement against the adjacent inside faces of the vertical inturned flanges 3 adjacent the lower terminal ends thereof. As in the case of the hinge brackets A and A', above described, the abutment face 25' of the nose portion 25 of hinge bracket B and the adjacent insert studs 23, define a groove therebetween which receives the adjacent terminal ends of the inturned flanges 3 of the pilaster body and the terminal ends of the lip portions 7 of the edging strip 6. When the corner bracket B is tilted into position, the spaced studs are driven under the adjacent terminal ends 4" of the pilaster lip portions 4 and into bracing engagement therewith. The spaced side seating faces 22' of this bracket will then seat against the outside face of the vertically extending ledge portions 11' adjacent the hole. The spaced rail portions 28 of the rearwardly extending wing section 26 will then also seat against the outside face of the horizontally extending ledge portions 11" of the pilaster body, with the lower leg of the Tinnerman nut 12 pocketed within the depressed center face 28' of the wing section 26, as indicated in FIGS. 13 and 14. A metal securing screw 13 may then be applied to extend through the bracket wing section 26 and into the deformed hole of the Tinnerman nut 12 to further lock and secure the lower corner bracket B in rigid position.

When the lower corner bracket B is fully applied to the lower end of the ceiling hung pilaster 1' as shown in FIG. 2, the curvilinear face 21' of its body section 21 will be in streamlined symmetry with the curvilinear face 6' of the edge moulding strip 6 extending thereabove, and with the lower end of the vertically extending moulding strip 6 in abutting relation to the square cut end 22 of its body section 21. The paired insert studs

23 extending from the square cut end 22 will also be snugly pocketed within the inner corners of the lower terminal end of the adjacent edging strip 6, and will also be positioned in bracing relation against the inside faces of the adjacent outturned lip portions 4 of the pilaster body, with the edging strip 6 firmly locked to the pilaster body by the outturned lip portions 4 thereof. The lower corner bracket B is additionally rigidly fixed to the lower end of the ceiling hung pilaster 1' by the securing screw 13 which extends through the wing section 26 thereof and is screwed into the Tinnerman nut 12 clamped to the terminal ends of the horizontally extending inturned flanges 3 of the pilaster body.

The door supporting hinge bracket G shown in FIGS. 15, 17, 18 and 19, is designed to be mounted on the jamb face of the hollow metal pilaster 1 or 1' and to seat against the adjacent flange portions 17 of the pilaster body as shown in FIG. 16, and held thereto by a snap fastener in the form of a snap lock channel 54. The hinge bracket G may be die cast as an integral unit to provide a door supporting arm section 20 extending from a body section 50 which presents a curvilinear outer face 50' in contour conformity to the outer faces of the curvilinear face portions 6' of the upper and lower edging strips 6 applied to the pilaster body. The hinge bracket G may be used as an upper hinge bracket, or a lower door supporting hinge bracket, by providing a pintle hole 20' therein to receive an upper door hinging pintle, or a pintle hole 20" therein which supports a lower pintle on which the door is swingably supported.

The bracket body section 50 may present square cut ends 50" against which the terminal ends of the upper and lower edge moulding strips 6 are designed to abut, to thereby provide substantially flush and single line joints therebetween. The upper and lower ends of the body section 50 may also be provided with a tongue or a pair of spaced vertically extending studs 51 at one or both ends thereof which are designed to telescope into the adjacent end of the semi-tubular edge moulding strip 6.

The body section 50 also presents a pair of spaced rear facing portions 52 which define a vertically extending locking groove 53 therebetween, as shown in FIGS. 15 and 19. The locking groove 53 presents side ledge portions 53' designed to interlock with a snap-lock channel 54 which is first applied to the jamb face of the pilaster body as shown in FIG. 16. The spaced rear facing portions 52 of the bracket body section 50 are designed to flatly seat against the outside faces of the inturned flange portions 17 of the pilaster body when the bracket body section 50 has been pushed into locking relation with the snap-lock channel 54.

The snap-lock channel 54 presents a web portion 54' which seats against the outside faces of the inturned flange portions 17 of the pilaster body. The snap-lock channel 54 also presents side flanges 54" terminating in resilient curvilinear rim portions 54'" designed to snap into interlocking engagement with the side ledge portions 53' of the locking groove 53 formed in the rear face of the bracket body section 50. The web portion 54' of the snaplock channel 54 is rigidly secured to an internal bracing plate 18 which seats against the inside faces of the inturned flange portions 17 of the pilaster body as shown in FIG. 16, and is secured thereto by suitable metal screws 18".

In manufacturing the pilasters 1 and 1' to support one or more of the hinge brackets G, the inturned flanges 3 of the pilaster facing sheets 2-2 are formed to provide the usual outturned lip portions 4 above and below the area where the hinge bracket G is to be applied, leaving lipless inturned flange portions 17 therebetween which provide a flat seat for the spaced seating portions 52 of the bracket body section 50. A sturdy bracing plate 18 is positioned adjacent the inside face of the inturned flange

portion 17 of one of the pilaster facing sheets and secured as by spot welds 17' thereto. After the reinforcing core 5 has been adhesively bonded to this pilaster facing sheet 2, the companion pilaster facing sheet 2 is applied thereover and adhesively bonded to the adjacent face of the reinforcing core 5. The inturned lip portions 4 are then secured together by the application of a series of spot welds 4' in the crotch therebetween as shown in FIG. 16. The terminal ends 4''' of the existing lip portions 4 are sufficiently spaced to permit the application of the body section 50 of the hinge bracket G to the inturned flange portions 17 therebetween. The inturned flange portions 17 of the second and companion pilaster facing sheet 2 may also be spot welded or screwed to the underlying bracing plate 18. The snaplock channel 54 is then placed in seating position against the outside faces of the flange portions 17, and rigidly held in position by two or more metal screws 18''' extending through the web portion 54' thereof and screwed into tapped holes provided in the internal reinforcing plate 18.

The bracket body section 50 is then applied by telescoping the locking groove 54 in the rear face thereof over the side flange portions 54'' of the snap-lock channel 54 until the resilient curvilinear rim portions 54''' thereof snap into interlocking engagement with the side ledge portions 53' of the locking groove. The spaced rear facing portions 52 of the body section will then snugly seat against the outside faces of the inturned flange portions 17 of the pilaster body. In applying the bracket body section 50 to the snap lock channel 54, one end of the body section 50 is first telescoped over the side flange portions 54'' of the snap lock channel 54 and the adjacent paired studs 51 telescoped under the adjacent terminal ends 4'' of the pilaster lip portions 4. The paired studs at the other end of the body section will then clear the adjacent terminal ends 4'' of the pilaster lip portions 4 therebelow, when the body section 50 is fully telescoped into locking engagement with the entire length of the side flange portions 54'' of the snap-lock channel 54. The body section 50 of the hinge bracket may then be vertically adjusted so that the paired studs 51 at both ends thereof will underlie and abut against the inner faces of both the upper and lower set of pilaster lip portions 4.

The upper and lower moulding strips 6 are then telescoped over the outwardly flared lip portions 4 of the pilaster body as indicated in FIG. 15, and the terminal ends thereof placed in abutting relation to the square cut ends 59'' of the bracket body section 50, and with the locking studs 51 snugly telescoped into the adjacent terminal end portion of the semi-tubular edging strip 50, and in abutting relation to the inner faces of the outwardly flared lip portions 4 extending above and below the body section of this hinge bracket.

The hinge bracket G is thus rigidly and securely mounted on the jamb face of the pilaster by the snap-lock channel 54 whose resilient curvilinear rim portions 54''' are in locking engagement with the side ledge portions 53' of the locking groove 53 extending vertically along the rear face of the bracket body section 50. This bracket is further braced by the spaced rear facing portions 52 extending along the locking groove 53, and which snugly seat against the outside faces of the inturned flange portions 17 of the pilaster body. The hinge bracket G may be further rigidly fixed to the jamb face of the pilaster body by the provision of tongues or studs 51 which project from the upper and lower ends of the bracket body section 50 and into the end of the adjacent semi-tubular edging strip 6, and with the three sides of each stud 51 in bracing relation to the inside faces of the curvilinear portion 6' and the inturned lip portion 7 of the edging strip 6, and the face or edge of the adjacent lip portion 4 of the pilaster.

As thus assembled, the curvilinear outer face 50' of the bracket body section 50 is in streamlined symmetry

with the outer curvilinear faces of the applied edging strips 6, with no bracket securing means exteriorly visible when the hinge bracket G is fully assembled on its supporting pilaster.

5 The spaced insert studs 23 associated with the brackets A, A' and B, and the similar insert studs 51 associated with hinge bracket G, provide a particularly effective means for rigidly securing these hinge brackets to the jamb portion of the pilaster, since these spaced insert studs telescope into the adjacent terminal end of the semi-tubular edge moulding strip 6 between the curvilinear facing portion 6' and inturned lip portions 7 thereof and thus are firmly locked thereto. These spaced insert studs permit extension of the terminal ends of the adjacent outwardly flared lip portions 4 of the pilaster body, to a point directly adjacent the end of the bracket body section, so the terminal end of the edge moulding strip is locked to the outturned lip portions 4 directly adjacent the terminal end of the bracket body section.

20 It will be particularly noted that all of the hinge brackets of this invention are directly supported from the jamb portion of a pilaster body, and do not overlap the side panel facing sheets of the pilaster body, and are particularly designed to be rigidly secured to the jamb edge portion of relatively thin pilaster bodies which may measure only one inch in thickness. The door supporting hinge and pilaster structures of this invention present an assembly wherein the exterior faces of the hinge brackets are in contoured symmetry with the exposed faces of 25 the pilaster edge moulding strips 6, and as assembled, present fine line butt joints therebetween which are scarcely discernible, and wherein the hinge bracket is securely locked and held in fixed position by internal locking elements, and/or by the use of insert studs, which project 30 from one or both ends of the bracket and which snugly telescope into the adjacent terminal end of a slideable semi-tubular edging strip.

35 Pilaster structures and hinge bracket assemblies made in accordance with this invention feature the elimination 40 of bracket side flanges and other projections heretofore used to secure the hinge bracket to the pilaster, and which provide areas for the collection of dirt and foreign matter which cannot be readily removed. The hinge brackets of this invention can be cast or formed in one 45 piece, at substantially less cost than door supporting hinge brackets heretofore made and used, and can be mounted on the jamb edge of the pilaster at the factory in precise door supporting alignment, and with less labor and less cost than the pilaster and hinge bracket assemblies heretofore made and used. The necessary modifications 50 to the jamb edge of the pilaster bodies can be accomplished in accordance with this invention at minimum cost when cutting and fabricating the panel facing sheets, or during assembly of the pilaster body.

55 While certain novel features of this invention have been disclosed herein and are pointed out in the claims, it will be understood that various omissions, substitutions, and changes may be made by those skilled in the art without departing from the spirit of this invention.

60 What is claimed is:

1. A door supporting assembly including in combination, a hollow metal pilaster presenting a jamb portion and a hinge bracket supported in cantilever suspension from said jamb portion; said pilaster being formed by a 65 pair of spaced sheet metal facing panels, a pair of aligned flanges extending inwardly from said facing panels, and a pair of outwardly flared lip portions extending from the adjacent inner edges of said inturned flanges and which terminate adjacent the upper end of said jamb portion; said hinge bracket including a body section seating against the jamb portion of the pilaster, a door supporting arm extending from the front face of said body section, and a pair of spaced locking studs extending from the upper end of said body section in straddling relation to the adjacent ends of the outwardly flared lip portions

of the pilaster and with at least the terminal end portion of each locking stud extending inwardly between the inner faces of the adjacent flange portion and the outwardly flared lip portion of the pilaster; a semi-tubular edging strip presenting a curvilinear facing portion terminating in inturned lip portions, said edging strip telescoping over the interlocking with the outwardly flared lip portions of the pilaster with its terminal end in abutting relation to the adjacent upper end of the body section of said hinge bracket, each of said locking studs having at least the terminal end portion thereof pocketed within a conforming hole defined by the inner faces of the lip portion and curvilinear facing portion of said edging strip and the inner face of the outwardly flared lip portion of the pilaster.

2. A door supporting assembly including in combination, a hollow metal pilaster presenting a jamb portion and a hinge bracket supported in cantilever suspension from said jamb portion, said pilaster being formed by a pair of spaced sheet metal facing panels, a pair of aligned flanges extending inwardly from said facing panels, a first pair of outwardly flared lip portions extending from the adjacent inner edges of said inturned flanges and which terminate adjacent the upper end of said jamb portion, and a second pair of outwardly flared lip portions extending inwardly from the adjacent inner edges of said inturned flanges and which terminate adjacent the lower end of said jamb portion; said hinge bracket including a body section seating against the jamb portion of the pilaster and presenting square cut ends seating between the terminal ends of the first and second pair of outwardly flared lip portions of the pilaster, a door supporting arm extending from the front face of the said body section, and a pair of spaced locking studs extending from each end of said body section and in straddling relation to the adjacent ends of the respective first and second pair of outwardly flared lip portions of the pilaster and with at least the terminal end portion of each locking stud extending inwardly between the inner faces of the adjacent flange portion and outwardly flared lip portion of the pilaster; a first semi-tubular edging strip and a second semi-tubular edging strip each presenting a curvilinear shaped facing portion terminating in inturned lip portions, said first and second edging strips telescoping over and interlocking with the respective first and second pair of outwardly flared lip portions of the pilaster with the terminal ends of the respective first and second edging strips in abutting relation to the adjacent upper and lower ends of the body section of said hinge bracket, each of said locking studs having at least the terminal end portion thereof pocketed within a conforming hole defined by the inner faces of the lip portion and curvilinear facing portion of the adjacent edging strip and the inner face of the adjacent outwardly flared lip portion of the pilaster; the front face of the body section of said hinge bracket being substantially flush with the exterior face of said first and second edging strips.

3. An integrally formed hinge bracket which includes, a body section having an arcuately contoured front face, a relatively flat end face and relatively flat rear face portions, a door supporting arm projecting from the contoured front face of said body section, an anchor section projecting rearwardly from said body section and between the rear face portions thereof, a nose extension projecting from one end of said anchor section and beyond the end face of the body section, said nose extension presenting a depressed abutment face inset rearwardly from the rear face portions of said body section and projecting beyond the end face thereof, and a pair of transversely spaced locking studs projecting longitudinally from the end face of the body section and in spaced relation to the abutment face of said nose extension, each of said locking studs being of lesser length than the length of the adjacently spaced abutment face of said nose extension and having a base end whose peripheral margins are

inset with respect to the front and rear faces of said body section so that the end face of the body section presents front and rear abutment shoulders.

4. An integrally formed hinge bracket which includes, a body section having an arcuately contoured front face, a relatively flat end face and relatively flat rear face portions, a door supporting arm projecting from the contoured front face of said body section, an anchor section projecting rearwardly from said body section and between the rear face portions thereof, a nose extension projecting from one end of said anchor section and beyond the end face of the body section, said nose extension presenting a depressed abutment face inset rearwardly from the rear face portions of said body section and projecting beyond the end face thereof, said depressed abutment face having a width which is not substantially less than two-thirds the transverse width of said body section, and a pair of transversely spaced locking studs projecting longitudinally from the end face of the body section and in spaced relation to the abutment face of said nose extension, each of said locking studs being of lesser length than the length of the adjacently spaced abutment face of said nose extension and having a base end of generally triangular cross-section whose peripheral margins are inset with respect to the front and rear faces of said body section so that the end face of the body section presents front and rear abutment shoulders.

5. An integrally formed hinge bracket which includes, a body section having an arcuately contoured front face, relatively flat upper and lower end faces and relatively flat rear face portions, a door supporting arm projecting from the contoured front face of said body section, an anchor section projecting rearwardly from said body section and between the rear face portions thereof, a nose extension projecting from the upper end of said anchor section and beyond the upper end face of the body section, said nose extension presenting a depressed abutment face inset rearwardly from the rear face portions of said body section and projecting beyond the upper end face thereof, a first pair of transversely spaced locking studs projecting longitudinally from the upper end face of the body section and in spaced relation to the abutment face of said nose extension, each of said first pair of locking studs being of lesser length than the length of the adjacently spaced abutment face of said nose extension and having a base end whose peripheral margins are inset with respect to the front and rear faces of said body section so that the upper end face of the body section presents front and rear abutment shoulders, and a second pair of transversely spaced locking studs projecting longitudinally from the lower end face of the body section, each of said second pair of locking studs having a base end whose peripheral margins are inset with respect to the front and rear faces of said body section so that the lower end face of the body section presents front and rear abutment shoulders.

6. An integrally formed hinge bracket which includes, a body section having an arcuately contoured front face, relatively flat upper and lower end faces and relatively flat rear face portions, a door supporting arm projecting from the contoured front face of said body section, an anchor section projecting rearwardly from said body section and between the rear face portions thereof, a nose extension projecting from the upper end of said anchor section and beyond the upper end face of the body section, said nose extension presenting a depressed abutment face inset rearwardly from the rear face portions of said body section and projecting beyond the upper end face thereof, said depressed abutment face having a transverse width which is not substantially less than two-thirds the transverse width of said body section and said anchor block having an inclined lower end which terminates adjacent the lower end face of said body section, a first pair of transversely spaced locking studs projecting longitudinally from the upper end face of the body section and in spaced relation to the abutment face

of said nose extension, each of said first pair of locking studs being of lesser length than the length of the adjacently spaced abutment face of said nose extension and having a base end whose peripheral margins are inset with respect to the front and rear faces of said body section so that the upper end face of the body section presents front and rear abutment shoulders, and a second pair of transversely spaced locking studs projecting longitudinally from the lower end face of the body section, each of said second pair of locking studs having a base end whose peripheral margins are inset with respect to the front and rear faces of said body section so that the lower end face of the body section presents front and rear abutment shoulders.

7. An integrally formed hinge bracket which includes, a body section having an arcuately contoured front face, a relatively flat upper end face and relatively flat rear face portions, a door supporting arm projecting from the contoured front face of said body section, an anchor section projecting rearwardly from said body section and between the rear face portions thereof, a nose extension projecting from the upper end of said anchor section and beyond the upper end face of the body section, said nose extension presenting a depressed abutment face inset rearwardly from the rear face portions of said body section and projecting beyond the upper end face thereof, a pair of spaced locking studs projecting longitudinally from the upper end face of the body section and in spaced relation to the abutment face of said nose extension, each of said locking studs having a base end whose peripheral margins are inset with respect to the front and rear faces of said body section so that the upper end face of the body section presents inner and outer abutment shoulders, and a wing section projecting rearwardly from the opposite end of said body section and anchor section and presenting a contoured outer face.

8. A door supporting assembly including in combination; a hollow metal pilaster formed by a pair of spaced facing panels, a pair of aligned flanges extending inwardly from said facing panels, a substantially rectangular bracket supporting hole formed in said aligned flanges, and a pair of outwardly flared lip portions extending above and terminating adjacent the upper edge of said bracket supporting hole and flaring outwardly from the inner edges of the inturned flanges extending above said bracket supporting hole; a hinge bracket having a body section presenting an arcuately contoured front face, a door supporting arm projecting from the contoured front face of the body section, an anchor section projecting rearwardly from said body section and fitted within said bracket supporting hole, said body section having a relatively flat upper end face positioned adjacent the upper transverse edge of said bracket supporting hole and a pair of transversely spaced and relatively flat rear face portions along the opposite sides of said anchor block seating against the outer faces of pilaster flange portions which define the sides of said bracket supporting hole, a nose extension projecting from the upper end of said anchor section and beyond the upper end face of the body section, said nose extension presenting a depressed abutment face inset rearwardly from the rear face portions of said body section and seating against the inner faces of the pilaster flanges extending above said bracket supporting hole, and a pair of transversely spaced locking studs projecting longitudinally from the upper end face of the body section and in spaced relation to the abutment face of said nose extension, said locking studs being of lesser length than the length of the adjacently spaced abutment face of said nose extension and defining a groove therebetween, each of said locking studs having a base end whose peripheral margins are inset with respect to the front and rear faces of said body section so that the upper end face of the body section presents front and rear abutment shoulders; and a semi-tubular edging strip presenting a curvilinear facing por-

tion terminating in inturned lip portions, said edging strip telescoping over and interlocking with the outwardly flared lip portions of the pilaster and having its terminal end in abutting relation to the adjacent upper end face of the body section of the hinge bracket and whereby a substantially flush joint is formed between the curvilinear facing portion of said edging strip and the arcuately contoured front face of said bracket body section, each of said locking studs having at least a terminal end portion thereof pocketed within the adjacent conforming hole defined by the inner faces of the lip portion and curvilinear facing portion of said edging strip and the inner face of the outwardly flared lip portion of the pilaster.

15. 9. A door supporting assembly including in combination; a hollow metal pilaster formed by a pair of spaced facing panels, a pair of aligned flanges extending inwardly from said facing panels, a substantially rectangular bracket supporting hole formed in said aligned flanges, 20 a first pair and a second pair of outwardly flared lip portions respectively extending above and below said bracket supporting hole and respectively terminating adjacent the upper and lower transverse edges of said bracket supporting hole and flaring outwardly from the inner edges 25 of the inturned flanges extending above and below said bracket supporting hole; a hinge bracket having a body section presenting an arcuately contoured front face, a door supporting arm projecting from the contoured front face of the body section, an anchor section projecting 30 rearwardly from said body section and fitted within said bracket supporting hole with the lower end of said anchor section seating on the lower transverse edge of said bracket supporting hole, said body section having relatively flat upper and lower end faces positioned adjacent the upper 35 and lower transverse edges of said bracket supporting hole and a pair of transversely spaced and relatively flat rear face portions along the opposite sides of said anchor block seating against the outer faces of pilaster flange portions which define the sides of said bracket supporting 40 hole, a nose extension projecting from the upper end of said anchor section and beyond the upper end face of the body section, said nose extension presenting a depressed abutment face inset rearwardly from the rear face portions of said body section and seating against the inner faces of the pilaster flanges extending above said bracket supporting hole, a pair of transversely spaced upper locking studs projecting longitudinally from the upper end face of the body section and in spaced relation to the abutment face of said nose extension, said upper 45 locking studs being of lesser length than the length of the adjacently spaced abutment face of said nose extension and defining a groove therebetween, and a pair of transversely spaced lower locking studs projecting longitudinally from the lower end face of the body section, each of said upper 50 and lower locking studs having a base end whose peripheral margins are inset with respect to the front and rear faces of said body section so that the respective upper and lower end faces of the body section present front and rear abutment shoulders; and first and second semi-tubular 55 edging strips each presenting a curvilinear facing portion terminating in inturned lip portions, each of said first and second edging strips respectively telescoping over and interlocking with the respective first and second pair of outwardly flared lip portions of the pilaster with its 60 terminal end in abutting relation to the adjacent end face of the body section of the hinge bracket and whereby substantially flush joints are formed between the curvilinear facing portions of said first and second edging strips and the arcuately contoured front face of said bracket body section, each of said locking studs having at 65 least a terminal end portion thereof pocketed within the adjacent conforming hole defined by the inner faces of the lip portion and curvilinear facing portion of said edging strip and the inner face of the outwardly flared 70 lip portion of the pilaster.

10. A door supporting assembly including in combination, a hollow metal pilaster formed by a pair of spaced facing panels, a pair of aligned vertical flanges and a pair of aligned horizontal flanges extending inwardly from said facing panels, a substantially rectangular bracket hole at a corner of the pilaster and formed in said vertical and horizontal flanges, a pair of vertically extending lip portions flaring outwardly from the adjacent inner edges of said vertical flanges and terminating adjacent the transverse upper edge of said bracket hole, and a pair of horizontal lip portions flaring outwardly from the adjacent inner edges of said horizontal flanges, said horizontal lip portions terminating in horizontally spaced relation to the lower transverse edge of the bracket hole to thereby provide for horizontal flange extensions which define the lower transverse edge of the bracket hole; a hinge bracket having a vertically extending body section presenting an arcuately contoured front face, a door supporting arm projecting from the contoured front face of the body section, an anchor section projecting rearwardly from said body section and fitted within said bracket hole, said body section having a relatively flat upper end face positioned adjacent the upper transverse edge of said bracket hole and a pair of transversely spaced and relatively flat rear face portions along the opposite sides of said anchor block seating against the outer faces of vertical flange portions which define the vertical sides of said bracket hole, a nose extension projecting from the upper end of said anchor section and beyond the upper end face of the body section, said nose extension presenting a depressed abutment face inset rearwardly from the rear face portions of said body section and seating against the inner faces of the vertical flanges extending above said bracket hole, a pair of transversely spaced locking studs projecting longitudinally from the upper end face of the body section and in spaced relation to the abutment face

of said nose extension, each of said locking studs having a base end whose peripheral margins are inset with respect to the front and rear faces of said body section so that the upper end face of the body section presents front and rear abutment shoulders, and a horizontal wing extension projecting rearwardly from the lower end of said body section and anchor section which presents a contoured outer face, relatively flat inner face portions seating against the outer faces of horizontal flange portions which define the horizontal sides of the bracket hole, and a relatively flat terminal end face; a vertically extending semi-tubular edging strip and a horizontally extending semi-tubular edging strip each presenting a curvilinear facing portion terminating in inturned lip portions, 15 said vertical edging strip telescoping over and interlocking with the vertically extending lip portions of the pilaster with its terminal end in abutting relation to the adjacent upper end face of the body section of the hinge bracket and whereby a substantially flush joint is formed between the curvilinear facing portion of said vertical edging strip and the arcuately contoured front face of said bracket body section, said horizontally extending edging strip telescoping over and interlocking with the horizontally extending lip portions of the pilaster with its terminal end 20 in abutting relation to the adjacent terminal end face of said wing section, each of said locking studs having at least a terminal end portion thereof pocketed within the conforming hole defined by the inner faces of the lip portion and curvilinear facing portion of said vertical edging strip and the inner face of the vertical lip portion of the pilaster.
